TAPE APPLICATOR OR LIKE ARTICLE

George H. Fritzinger, West Orange, N. J.

Application August 7, 1957, Serial No. 47,261

Term of patent 14 years

(Cl. D74—1)

Figure 1 is a side elevational view of a tape applicator showing my new design, the side opposite thereto being substantially similar in appearance;

The dominant features of my new design are shown in solid lines in the drawing.

I claim:

The ornamental design for a tape applicator or like article, substantially as shown and described.
